Attorney.

UNITED STATES PATENT OFFICE.

GEORGE F. CLARK, OF UTICA, NEW YORK.

DESIGN FOR A SPRAYER-BODY.

SPECIFICATION forming part of Design No. 33,581, dated November 20, 1900.

Application filed October 27, 1900. Serial No. 34,668. Term of patent 3¹ years.

To all whom it may concern:

Be it known that I, GEORGE F. CLARK, a citizen of the United States, residing at Utica, in the county of Oneida and State of New York, have invented and produced a new and original Design for a Sprayer-Body, of which the following is a specification, reference being had to the accompanying drawings, forming a part hereof.

Figure 1 shows a perspective view of a sprayer-body of my design. Fig. 2 shows an end view of the same.

The feature of the design is the form and arrangement of the parts constituting the sprayer-body—that is to say, the lower cylindrical portion 1, a superposed similar cylindrical body portion 2, the small cylindrical

portion 3, arranged with reference to the portions 1 and 2, as shown, and the loop or handle 4, arranged on top of the portion 2, substantially as shown.

Having described my invention, what I claim as new, and desire to secure by Letters Patent, is—

The design for a sprayer-body, substantially as herein shown and described.

In witness whereof I have hereunto subscribed my name, in the presence of two witnesses, this 20th day of October, 1900.

GEO. F. CLARK.

Witnesses:

S. A. BROWN,
CHAS. G. IRISH.
